REFRIGERATING APPARATUS

Jewel C. Chambers, Dayton, Ohio, assignor, by
mesne assignments, to General Motors Corpora-
tion, a corporation of Delaware

Application November 29, 1933, Serial No. 700,171

15 Claims. (Cl. 62—6)

This invention relates to refrigerating apparatus, and is directed to the conditioning of air in a building or the like in which the conditioning load varies in several parts of the building at certain periods of time. Thus in a building where the sun shines on opposite sides thereof, the conditioning load is greater on one side at one time of the day and is greater on the other side of the building at another time of the day. It is among the objects of this invention to provide an air conditioning apparatus which may shift its conditioning capacity to meet these changing conditions.

Further objects and advantages of the present invention will be apparent from the following description, reference being had to the accompanying drawings, wherein a preferred form of the present invention is clearly shown.

In the drawings:

Fig. 1 is a diagrammatic representation of one embodiment of my invention; and

Fig. 2 is a diagrammatic representation of another embodiment of my invention.

To illustrate my invention, a building, generally designated as 10, may have means 11 and/or 12 for modifying the condition of the air at various parts or rooms 10a and 10b in the building. While I prefer to use my invention with a plurality of modifiers, certain aspects of my invention may be applied where only one modifier is used. Thus where only one such modifier is used, conditions may arise wherein the modifier need not operate during a certain portion of the day, but should operate during other parts of the day. It is within the purview of my invention that automatic means responsive to the sun's rays may be provided thus automatically to control the single modifier. Where two or more air modifiers are used, it is within the purview of this invention to provide means for automatically changing the operation of the modifiers as the conditioning load shifts throughout the building.

To accomplish the foregoing, the modifier 11 may be in the form of an evaporator 13 through which air is blown by the electrically driven blower 14. The second air modifier 12 may be in the form of a second evaporator 15 through which air is blown by the electrically driven blower 16. The evaporator 13 is connected to a first refrigerant liquefying unit 17, preferably in the form of a compressor 18, condenser 19 and receiver 20a in closed refrigerant flow connection with the evaporator 13, the compressor 18 being driven by an electric motor 20. The

evaporator 13 may be provided with any suitable means of properly maintaining the refrigerant therein, and to this end an automatic expansion valve 21 is provided, having a thermostatic bulb 21a in contact with the outlet of the evaporator 13. This type of valve is constructed to maintain the evaporator 13 substantially in a liquid refrigerant flooded condition.

The second evaporator 15 is connected to a second refrigerant liquefying unit 22, similar to the first refrigerant liquefying unit 17, and which preferably comprises a compressor 23, condenser 24, refrigerant receiver 25 in closed refrigerant flow circuit with the evaporator 15, a suitable refrigerant flow valve, in the form of an automatic expansion valve 26 having thermostatic bulb 26a, being provided, the action of valve 26 being similar to the action of valve 21.

In the modification shown in Fig. 1, a booster 20 is provided to enhance the conditioning power of either or both the modifiers 11 and 12. In this particular embodiment, the booster is in the form of a booster refrigerant liquefying unit 27, preferably comprising a compressor 28, condenser 29 and receiver 30, constructed and arranged so that it may be connected in refrigerant flow relationship with either or both the evaporators 13 and 15.

In order to permit the booster 27 to be connected with either or both of the modifiers, the receiver 30 is connected with a liquid refrigerant pipe 31, having branches 32 and 33 which are connected respectively with the liquid refrigerant pipes 34 and 35 which connect respectively the receiver 25 with the evaporator 15 and the receiver 20 with the evaporator 13. Likewise the evaporated refrigerant line 36, which leads to the compressor 28 is connected by branches 37 and 38 respectively with the evaporated refrigerant lines 39 and 40 which connect respectively evaporator 15 with the compressor 23, and evaporator 13 with compressor 18.

Suitable valves, preferably in the form of solenoid valves 41, 42, 43 and 44 are provided for connecting the booster 27 with either of the modifiers 11 and 12. If the connection is to be automatic, automatic means, responsive to the shifting conditions of the building, are provided for properly actuating these valves. To this end, a first sun ray-sensitive instrument 45 is provided for the modifier 11 and evaporator 13 and a second sun ray-sensitive instrument 46 is provided for the modifier 12 and evaporator 15. These ray-sensitive instruments are constructed and arranged to change the operation of at least one of

the modifiers in response to the action of the sun's rays on the instrument. This is accomplished by causing these instruments to connect the booster refrigerant liquefying unit 27 with either or both the evaporators 13 and 15 thus to enhance the conditioning power of these evaporators by enhancing the refrigerant liquefying capacities connected with the evaporators.

The connection of the booster 27 by means of the instruments 45 and 46 is accomplished by suitable electrical relays. Thus when sun's rays become sufficiently effective on the instrument 45, the relay 47 is energized. This causes the relay 48 to be energized through the action of the current flowing through the transformer 49, which in turn is energized by the line current from source 50. When the more powerful relay 48 is closed, current flows through the line 52 and 53 to the solenoid valves 44 and 42 and back to the main line 54, thus opening valves 44 and 42 and thus connecting the booster 27 in refrigerant flow relationship with the evaporator 13. It is also desirable simultaneously to cause the refrigerant liquefying unit 27 to start operating if the same is not already operating. This is accomplished by providing a relay 51 which is energized by the relay 48, which relay 51 causes current to flow through the line 54 to the motor 55 which drives the compressor 28, thus causing the unit 27 to start operating. Also, if the compressors in these units have bodies of lubricant which may enter into flow relationship with the refrigerant, it is desirable to provide a lubricant flow connection between the compressors which connection is opened when the booster is connected with either of the other refrigerant liquefying units. Thus a lubricant line 56 is provided with the solenoid valve 57 which is energized through the line 58 when the relay 48 is closed, and thus the oil in the crankcase of the compressors 18 and 28 attain a common level at the opening of the valve 57. If, therefore, there is any tendency for the oil flowing through the refrigerating system to accumulate in either of the compressors 18 or 28, the connection 56 overcomes this tendency and prevents the accumulation of oil in one compressor to the detriment of the other.

Preferably the air modifier 11 is automatically controlled in accordance with conditions in the enclosure 10a in which it is located. Thus the condition sensitive instrument 60, which may be a dry bulb thermostat, a wet bulb thermostat, a hygrostat or any other suitable automatic instrument, permits the flow of electric current through the line 61 when conditions require it, and this flow causes the blower 14 to operate and simultaneously causes the motor 20 to operate, thus controlling the operation of the unit 17.

When the conditioning load shifts to the other side of the building, the ray-sensitive instrument 46 is adapted to connect the booster 27 with the modifier 12 in substantially the same manner that the ray-sensitive instrument 45 connects the booster with the modifier 11. Thus when the sun's rays become effective on the instrument 46, the relay 70 is energized thus closing its switch and energizing the relay 71 through the action of transformer 72. When the switch of relay 71 is closed, current flows through the lines 73 and 74 to the solenoid valves 41 and 43, opening them and thus connecting the unit 27 with the evaporator 15. Simultaneously the valve 76 is energized through line 77. When the valve 76 is opened, the oil

line 78 permits the oil level in the crankcases of compressors 28 and 23 to equalize.

Means are provided for causing the unit 27 to operate when it is connected with the modifier 12. This is accomplished because when the relay 75 is energized by the flow of current through the lines 73 and 74, the switch of the relay 75 is closed and permits current to flow through the line 83 to the motor 55 which drives the compressor 28.

The modifier 12 is operated in accordance with conditions in the enclosure in which the modifier is located. Thus the condition sensitive instrument 80, similar to instrument 60, permits the flow of current through the line 81 when conditions require it, thus actuating the blower 16 and the motor 82 which drives the compressor 23.

From the foregoing it will be seen that the modifiers 11 and 12 maintain normal desired conditions in the rooms in which they are located. When the conditioning load shifts or increases abnormally in the building and the sun's rays become effective on either of the instruments 45 or 46, these instruments change the operation of the corresponding modifier by connecting the booster refrigerant liquefying unit 27 with the corresponding evaporator. This action naturally changes or modifies the action of the refrigerant liquefying unit which is permanently connected to the evaporator, by boosting its refrigerant liquefying power. If the sun's rays become effective on both of the instruments 45 and 46, then the booster 27 is connected to both modifiers 11 and 12 by the opening of all of the valves 41, 42, 43 and 44.

In the modification shown in Fig. 2, the action of the modifiers 111 and 112 is changed by changing the speed of the operation of the refrigerant liquefying units 117 and 122 respectively, rather than by connecting a booster to them. To this end, the motors 120 and 122 are of the two-speed, or plural speed, variety. These motors drive respectively compressors 118 and 123. When the sun's rays become effective on the ray-sensitive instrument 145, the relay 147 is energized. This in turn energizes relay 201 in such a manner that it causes the compressor 118 to operate at a higher speed. This obviously increases the modifying capacity of the evaporator 113 so that the modifying action of the modifier 111 is changed.

The remaining portions of the system are substantially the same as in Fig. 1. Thus the compressor 118 discharges into a condenser 119 and a receiver 120a. Refrigerant flows through the liquid line 135 through the automatic expansion valve 121 into the evaporator 113, the evaporated refrigerant returning to the compressor 118 through the line 140. The operation of the modifier 111 is also governed by conditions in the compartment in which it is placed. Thus a condition responsive instrument 160, similar to instrument 60, permits current to flow through the line 161, when required by conditions, to actuate the blower 114, passing also through control 201 in a manner to cause the motor 120 to operate at the normal or slower speed. The unit 117 thus starts and stops, operating at the normal or slower speed, until such a time as the sun's rays become effective and the instrument 145, when the unit 117 operates at the higher or abnormal speed.

The modifier 112 is similar under the control of the ray-sensitive instrument 146 and the condition sensitive instrument 180. When the sun's rays become effective on the instrument 146, the relay 171 is energized which in turn energizes the relay 202 through the action of the transformer 172. When the relay 202 is closed, current flows through the speed control 203 in a manner which causes the motor 182 to operate at the higher speed. When the condition sensitive instrument 180 is energized, current flows through the line 181 to the blower 116 and to the speed control device 203 in a manner to cause the motor 182 to operate at the slower speed, when the instrument 146 is not under the action of the sun rays, and to operate the motor 182 at the higher speed when the instrument 146 is under the influence of the sun's rays.

The compressor 123 is connected to a condenser 124, a receiver 125, a liquid refrigerant line 134, an automatic expansion valve 126 to the evaporator 115. The evaporated refrigerant returns through the line 129 to the compressor 123.

The parts in Fig. 2 which are numbered 100 higher than corresponding parts in Fig. 1, have substantially the same function, and operate substantially in the same manner as such corresponding parts in Fig. 1, the only difference being that the liquefying units in Fig. 2 have their capacity increased by a change in speed rather than by the help of a booster.

While the form of embodiment of the invention as herein disclosed, constitutes a preferred form, it is to be understood that other forms might be adopted, all coming within the scope of the claims which follow.

What is claimed is as follows:

1. In an air conditioning apparatus, a first air cooler, a second air cooler, a booster, a first ray-sensitive instrument for said first air cooler, a second ray-sensitive instrument for said second cooler, said instruments connecting said booster to said coolers in response to the action of rays on said instruments.

2. In an air conditioning apparatus, a first evaporator, a first refrigerant liquefying unit connected to said evaporator, a second evaporator, a second refrigerant liquefying unit connected to said second evaporator, a booster refrigerant liquefying unit, and means for selectively connecting said booster liquefying unit to either evaporator.

3. In an air conditioning apparatus, a first evaporator, a first refrigerant liquefying unit connected to said evaporator, a second evaporator, a second refrigerant liquefying unit connected to said second evaporator, a booster refrigerant liquefying unit, and means for automatically connecting said booster with either of said evaporators in accordance with environmental conditions.

4. In an air conditioning apparatus, a first evaporator, a first refrigerant liquefying unit connected to said evaporator, a second evaporator, a second refrigerant liquefying unit connected to said second evaporator, a booster refrigerant liquefying unit, temperature responsive means controlling the operation of said first refrigerant liquefying unit, and means for automatically connecting said booster with either of said evaporators in accordance with environmental conditions.

5. In an air conditioning apparatus, a first evaporator, a first refrigerant liquefying unit connected to said evaporator, a second evap-

orator, a second refrigerant liquefying unit connected to said second evaporator, a booster refrigerant liquefying unit, a first temperature responsive means controlling the operation of said first refrigerant liquefying unit, a second temperature responsive means controlling the operation of said second refrigerant liquefying unit, and means for automatically connecting said booster with either of said evaporators in accordance with environmental conditions.

6. In an air conditioning apparatus, a first evaporator, a first refrigerant liquefying unit connected to said evaporator, a second evaporator, a second refrigerant liquefying unit connected to said first and second evaporators, a first ray-sensitive instrument for said first evaporator, a second ray-sensitive instrument for said second evaporator, constructed and arranged to change the operation of at least one of said refrigerant liquefying units in response to the action of rays on said instruments.

7. In an air conditioning apparatus, a first evaporator, a first refrigerant liquefying unit connected to said evaporator, a second evaporator, a second refrigerant liquefying unit connected to said second evaporator, a booster refrigerant liquefying unit, a first ray-sensitive instrument for said first evaporator, a second ray-sensitive instrument for said second evaporator, said instruments connecting said booster refrigerant liquefying unit to either of said first two named refrigerant liquefying units in response to the action of rays on said instruments.

8. In an air conditioning apparatus, a first evaporator, a first refrigerant liquefying unit connected to said evaporator, a second evaporator, a second refrigerant liquefying unit connected to said first evaporator and said second evaporator, a first ray-sensitive instrument for said first evaporator, a second ray-sensitive instrument for said second evaporator, constructed and arranged to change the speed of operation of at least one of said refrigerant liquefying units in response to the action of rays on said instruments.

9. In an air conditioning apparatus; an evaporator, a first refrigerant liquefying unit connected to said evaporator, a booster refrigerant liquefying unit, a ray sensitive instrument automatically connecting said booster refrigerant liquefying unit to said evaporator in response to the action of rays on said instrument.

10. In an air conditioning apparatus; an evaporator, a first refrigerant liquefying unit connected to said evaporator, temperature responsive means controlling the operation of said first refrigerant liquefying unit, a booster refrigerant liquefying unit, a ray-sensitive instrument automatically connecting said booster refrigerant liquefying unit to said evaporator in response to the action of rays on said instrument.

11. In an air conditioning apparatus, a first evaporator, a first refrigerant liquefying unit connected to said evaporator, a second evaporator, a second refrigerant liquefying unit connected to said first evaporator and said second evaporator, temperature responsive means controlling the operation of said first refrigerant liquefying unit, and a ray-sensitive instrument controlling the operation of one of said refrigerant liquefying units in response to the action of rays on said instrument.

12. In an air conditioning apparatus, a first evaporator, a first refrigerant liquefying unit connected to said evaporator, a second evap-

rator, a second refrigerant liquefying unit connected to said first evaporator and said second evaporator, a first temperature responsive means controlling the operation of said first refrigerant liquefying unit, a second temperature responsive means controlling the operation of said second refrigerant liquefying unit, and a ray-sensitive instrument controlling the operation of one of said refrigerant liquefying units in response to the action of rays on said instrument.

13. In an air conditioning apparatus, a first evaporator, a second evaporator, common refrigerant liquefying means connected to both of said evaporators, and ray-sensitive means for automatically increasing the refrigerating capacity of one of said evaporators in response to the action of the sun's rays.

14. In an air conditioning apparatus for a building or the like, heat absorbing means having localized cooling effect in a plurality of zones in said building, heat dissipating means connected to said heat absorbing means and a ray-sensitive control automatically controlling the localized cooling effect in one of said zones in response to the action of the sun's rays.

15. In an air conditioning system for a building or the like, a first evaporator within said building, a second evaporator within said building, common refrigerant liquefying means connected to said evaporators, and means responsive to a condition outside of said building for automatically increasing the refrigerating capacity of one of said evaporators.

JEWEL C. CHAMBERS.
